(57) **CLAIM**

The ornamental design for a guitar end pin, as shown and described.

DESCRIPTION

FIG. 1 is a front elevation view of a guitar end pin showing my new design, the rear elevation view being a mirror image; FIG. 2 is a first side elevation view thereof, the second side being a mirror image;

FIG. 3 is a top plan view thereof; and,

FIG. 4 is a bottom plan view thereof.

The elevation view of the pin in FIG. 1 rotated 180° is the same as FIG. 1 and the elevation view of the pin in FIG. 2 rotated 180° is the same as FIG. 2.

1 Claim, 1 Drawing Sheet

FIG. 3

FIG. 1

FIG. 2

FIG. 4
